UNITED STATES PATENT OFFICE.

GEORGE CROMPTON AND HORACE WYMAN, OF WORCESTER, MASSACHUSETTS,
ASSIGNORS TO SAID CROMPTON.

MECHANICAL MOVEMENT.

SPECIFICATION forming part of Letters Patent No. 336,624, dated February 23, 1886.

Application filed September 11, 1885. Serial No. 176,836. (No model.)

To all whom it may concern:

Be it known that we, GEORGE CROMPTON and HORACE WYMAN, both of the city and county of Worcester, State of Massachusetts, have 5 invented an Improvement in Mechanical Movements, of which the following description, in connection with the accompanying drawings, is a specification, like letters on the drawings representing like parts.

10 This invention has for its object the production of a novel and simple mechanism whereby a bar or rod may be reciprocated for different distances in one or the other direction, and be left at rest in either one of several defined positions, the time occupied in the movement of the rod being the same, whether it is made to pass from one to its next position or from its extreme positions.

15 In the mechanical movement herein described there are employed a main and an auxiliary lever, the fulcrum of the main lever being on the auxiliary lever, all as usual; but instead of holding the auxiliary lever so that it has but two positions under the control of its auxiliary devices we have provided means 20 whereby the fulcrum of the auxiliary lever may be made to occupy different positions, which enable the rod to be moved for a greater distance, and to be left in a greater number 25 of intermediate positions, than if the fulcrum of the auxiliary lever were fixed or movable, the movement shown resulting in six different positions.

30 Our invention consists, essentially, in a mechanical movement composed of an auxiliary or short lever, a main lever mounted thereon, a rod and connections between it and the said main lever, and two connecting-rods, and two cranks to move them, combined with a link or 35 slide joined with the fulcrum of the auxiliary lever, and with means to move the said link or slide and fulcrum of the auxiliary lever, whereby the fulcrum of the main lever is 40 made to occupy either one of the two different positions, and the said lever be made movable on its fulcrum in such positions.

45 Figure 1 in side elevation represents a block on which are mounted devices to enable our invention to be understood; Fig. 2, a top view thereof, and Fig. 3 a diagram illustrat-

ing different positions which the devices may be made to assume by stopping the cranks in different positions.

The board A, which may be part of a machine frame or other thing with which the devices to be described are to be used, has upon it suitable guides, *a a*, for the rod B, which is to be reciprocated longitudinally over different distances in the same interval of time, the said rod being marked to indicate 55 different steps or divisions, as from 1 to 6, inclusive, the block being marked by a line, *o*, to indicate the effective position of the rod, it being possible by the devices to be described to leave any step or division of the said rod with its bottom line opposite the line *o*. The rod B has joined to it a cord or chain, *b*, which, extended over a pulley, *b'*, is attached to one end of the main lever *c*, having its fulcrum at *c'* on the auxiliary lever *d*, the fulcrum *d'* of which is made to enter the guide *d'*. The fulcrum *d'* of the auxiliary lever has attached to it the link or slide *d''*, pivoted to the fulcrum-moving lever *e*, mounted on a pin or stud *e'*. The upper end of the levers *d c e* have attached to them, respectively, the connecting-rods *d''', c'', e''*, the said connecting-rods being joined, respectively, to the cranks *d''' c''' e'''*, mounted, as herein shown, on the stud *g*.

The cranks herein shown are composed of 70 disks with attached crank-pins, all the disks being on one stud, but in practice the disks will be toothed, each will turn on a pin carried by a vibrator, and each disk will, at the desired time and in the desired order, be given 75 a little more than a semi-rotation by partial gears, all as in United States Patent No. 281,842, dated July 24, 1883, to which reference may be had. The movement of lever *e* insures two positions for the fulcrum of the 80 auxiliary lever, and in either of its two positions it may be turned by the crank *d'''* and connecting-rod *d''*. The change of position of the fulcrum *d'*, (see the diagram Fig. 3,) and the movement of the lever *d* thereon, also effect 85 changes of the fulcrum *e'* of the main lever, as shown by the said diagram, and by moving the lever *e* on the fulcrum *c'* in any of its four positions, Fig. 3, the end of the lever *c*, to which the cord *b* is attached, is made to occupy 90 95 100

one of six positions indicated in the said figure, the rod B being correspondingly moved with relation to the lever o.

We claim—

5 The main lever, and the auxiliary lever on which the main lever has its fulcrum, and the link or slide to move the fulcrum of the said auxiliary lever, combined with means, substantially as described, to move the said link or slide and the said main and auxiliary levers, as and for the purpose set forth.

In testimony whereof we have signed our names to this specification in the presence of two subscribing witnesses.

GEO. CROMPTON.
HORACE WYMAN.
